UNITED STATES PATENT OFFICE.

WILLIAM R. RIGHTOR, OF HELENA, ARKANSAS.

IMPROVEMENT IN APPARATUS FOR RELIEVING GROUNDED VESSELS.

Specification forming part of Letters Patent No. 142,732, dated September 9, 1873; application filed May 23, 1873.

To all whom it may concern:

Be it known that I, WILLIAM R. RIGHTOR, of Helena, Phillips county, Arkansas, have invented a certain Improved Apparatus for Relieving Grounded Steamboats, of which the following is a specification:

My invention relates to a means of relieving vessels grounded on the bars of rivers; and consists of pipes laid longitudinally (either fixed or movable) on the deck of the vessel, and in communication with water-pumps or the steam-space of the boiler, and furnished with a number of coupling-joints or mouths, to which may be coupled a pipe having a vertical and a horizontal portion, the latter of which consists of sections or joints, so as to be adjustable in length, and is made so as to extend beneath the bottom of the boat. This pipe turns on the vertical portion as an axis, and carries around the horizontal portion, so that the open end of the latter may be directed to throw a jet against the part of the sand-bar on which the boat is lodged, and cause the sand to be carried away by the current.

In the drawings, Figure 1 shows a transverse section of the boat with one end of the same in perspective. Fig. 2 is a side view of a boat on a smaller scale.

A is the deck, and B the guards of the boat. C is a longitudinal pipe, secured above or beneath the deck, and in communication with the steam-space of the boiler, or with the doctor or other pump, or both boiler and pump, by pipes D, which are furnished with suitable valves d. E are discharge pipes or mouths, furnished with a valve, e, which is ordinarily closed. F is a socket-head, which may be coupled to either of the mouths E, and in which turns a pipe, G. The turn-joint of the pipe G in the head F is so constructed

that the water shall pass freely from the mouth E into pipe G in all positions of the latter. H is a lever, by which the pipe G may be turned in the head F. At the lower end of the vertical part G is an extension, I, reaching in a horizontal direction. The part I is preferably formed of a number of removable sections, i, so as to render it adjustable in length, as may be required. g are apertures in the deck, through which the pipe G passes.

The operation of my improvement is as follows: When the boat is found to be aground on a bar, K, the position of the latter is determined by sounding or otherwise, and the pipe G, by its socket-head and coupling f, secured to that mouth E which is in the proper position to admit of the jet-mouth of pipe I to be brought to bear upon the sand-bar, to stir it up beneath the bottom of the boat. As the sand is stirred up, and the loose sand carried away by the current, the pipe I is swung around, by means of the lever H, so as to play upon a fresh part of the bar; and after all within its scope has been swept away from beneath the vessel it may be changed to another mouth, E, to complete the work. The pipe I may be adjusted in length by attachment or removal of one or more of the sections i.

I claim as my invention—

The vertical pipe G, having a horizontal extension or discharge pipe, I, and provided with a swivel-bearing in the removable head F, whereby it is adapted to be rotated, when used in combination with the pipe C, in the manner and for the purpose described.

WILLIAM R. RIGHTOR.
